ADJUSTABLE MARKER

Lewis S. Murphy, Marion, Ind., assignor to Chicago Railway Equipment Company, Chicago, Ill., a corporation of Illinois

Application June 19, 1933, Serial No. 676,448

4 Claims. (Cl. 88—82)

This invention relates to lens mountings and particularly to devices placed along highways to reflect the light from automobile lamps for indicating sharp turns, bridge abutments, curbs and other traffic hazards.

The invention may be used also for signs generally and wherever it is desired to utilize a simple lens mounting which may be tilted to properly direct or reflect light rays.

10 Road markers and signs of the reflecting type, in particular, in order to be clearly visible to automobile drivers, must be in position to reflect light from the headlights towards the driver's seat. Thus where the mounting surface of the 15 marker support is improperly inclined, or unsuitable for mounting the marker for any other reason, a special support for the marker must be provided.

The main object of the present invention is to 20 provide a lens mounting of the above type which may be applied to the surface of a support regardless of the inclination thereof, the body of the marker holding the lens being adjustable to the proper angle.

25 This object and others hereafter appearing are attained substantially in the devices illustrated in the accompanying drawings showing markers each including a stationary base to be secured to the support, or object to be marked, and a 30 body part mounting the lens and itself adjustably on the stationary base.

Figure 1 is a front view of one form of the invention, a portion of the lens and its casing being broken away.

35 Figure 2 is a side view of the same, partly in section, taken on the line 2—2 of Figure 1.

Figure 3 is a side view of a modified form.

Figure 4 is a section through the longitudinal center line of another form.

40 Figure 5 is a side view of the same.

Figure 6 is a section showing another modification.

Figure 7 is a front view of the same.

45 Figure 8 is a view similar to Figure 7 but showing a detail.

The device in Figures 1 and 2 comprises a base portion 1, perforated at 2 for attaching bolts or screws, and provided with a central projection 3 with an arcuately depressed forward or outer web 4. Web 4 is slotted longitudinally, as at 5.

50 Seated against web 4 is the convex rear surface of body part 6 of the marker forming the lens housing. A screw 7, threaded into the rear wall of body 6, extends through slot 5 and the

head thereof overlaps the edges of the slot and prevents separation of the base and body parts while at the same time permitting relative movement of the same within limits defined by the slot. The screw 7 may be tightened in any selected relative position of the base and body parts to frictionally maintain the same in said position. Obviously, the screw 7 cannot be tampered with to change the angle of the lens holder so long as the marker remains secured 10 to its support.

Within the cup-shaped body 6 is a reflecting lens 8 which is held in position by a ferrule 9 of lead or similar ductile material inserted from the outside and upset by a circular tool to snugly 15 grip the abutting walls of the body and lens. This ferrule is shown and claimed in my co-pending application, Serial No. 676,447 filed of even date herewith.

In Figure 3 the base portion 10 includes a plurality of pocketed projections 10a for a battery of adjustable lens holders 11. The details of this device are the same as in the form previously described.

In Figure 4, the base portion 12 is provided 25 with a hemispherical seat 13 for the similarly shaped rear portion of the lens holder 14. A threaded collar 15, which may be locked in place by suitable means, not shown, maintains the ball joint connection between the base and lens 30 holder parts, and a screw 15a serves to secure the parts in any selected relative position. The lens 16 is secured in position by means of a lead ferrule 17, as in the previous figures.

In Figures 5 to 8, the marker base 23 is applied 35 to a post 24 and has a V-shaped projection 25 disposed to seat in any of the radial serrations 26 in the abutting surface of the lens holder 27. The lens holder is secured to the base by means of a set screw 28, which may be loosened or tightened 40 to permit rotation of the lens holder or to draw together the holder and base in the adjusted position. Engagement of projection 25 and one of the registering serrations 26 cooperates with the frictional engagement between the body and the enlarged head of the set screw to effectually prevent further rotation of the holder while the screw 28 is tight.

In each form of the invention the longitudinal 50 axis of the reflecting lens unit is non-coincident with the axis of its movement on the base member and the direction of the lens longitudinal axis may be varied to adjust the lens as required.

Each of the forms illustrated is simple and rug- 55

ged and thus adapted for use along the highways and at the same time may be easily adjusted without the necessity of shifting the entire marker. Obviously, various details of the embodiments illustrated may be varied as will occur to those skilled in the art, and exclusive use of all such modifications as come within the scope of the appended claims is contemplated.

What is claimed is:

- 10 1. A traffic marker comprising a base part for attachment to a support and having a portion forming a curved seat, a body part having a portion movably fitting against said seat, a reflecting lens unit immovable on said body part with its longitudinal axis disposed to be shifted to different directions when said parts are moved relative to each other, a slot in one of said parts, and a screw threaded in the other of said parts and extending through said slot, the screw head overlapping the edges of said slot and preventing separation of said parts with said screw in operative position, said screw serving to frictionally secure said parts in the selected adjustment and said head being enclosed between said body part and said support and being inaccessible for varying said adjustment when said base part is attached to the support.
- 20 2. A traffic marker comprising a base part having a surface for attachment to a support said base part having a slot, a body part seating against said base part and including a reflecting lens unit, and a screw threaded in said body part and extending through said slot, said screw cooperating with said parts to prevent separation of the same, to guide the relative movement thereof, or immovably secure the same in the selected adjustment, the screw head being enclosed between

said body part and said support and being inaccessible for varying said adjustment when said base part is attached to the support.

3. A traffic marker comprising a base member for direct fixed attachment to a support, a housing rotatably mounted on said base member, a reflecting lens unit immovably secured in said housing, the longitudinal axis of said lens unit being noncoincident with the axis of rotation of said housing on said base member, means for immovably securing said housing in adjusted position on said base member independently of means used for attaching said base member to a support, said securing means including a manually operable element within said base member for locking or releasing said securing means, said element being covered by a support when said base member is attached thereto.

4. A traffic marker comprising a base member having a side forming a seat facing in one direction and having a side arranged for direct fixed attachment to a support and provided with an opening, a body member rotatably mounted on said seat, a reflecting lens unit carried by said body member with its longitudinal axis disposed at an angle to the axis of rotation of said body member on said base member, there being elements on opposing faces of said base member and said body member arranged to positively interengage to prevent relative rotation when said parts are drawn together, and means for assembling said base member and body member and, when tightened, to draw said base member and said body member together, said means being surrounded by said base member and covered by a support on which said base member is mounted.

LEWIS S. MURPHY.
